(57) **CLAIM**

The ornamental design for a surveillance camera as shown and described.

DESCRIPTION

FIG. 1 is a bottom perspective view of a surveillance camera, showing the new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a sectional view taken along the line 8-8 in FIG. 2.

The broken lines depict parts of the surveillance camera that form no part of the claimed design.
